SIDE WALL CORE TAKING APPARATUS

Henry U. Garrett and Norman F. Brown, Longview, Tex., assignors, by mesne assignments, to Henry U. Garrett, Longview, Tex.

Filed May 1, 1957, Ser. No. 656,383

12 Claims. (Cl. 255—1.4)

This invention relates to tools for taking core samples from a well formation and more particularly to tools for taking core samples from the side wall of a well.

Cores are taken from a well wall by driving a tubular core drill into the wall and retracting the drill. Core catchers in the drill latch on to the core. As the core must be broken loose from the well wall and the retracting pull is usually at an angle to the longitudinal axis of the drill, great force must be exerted to retract the drill and core.

In core drills of the type shown in U.S. Letters Patent to J. R. Yancy et al. No. 2,558,227, wire lines used to retract the core drill are sometimes pulled in two in an attempt to retract a stuck core drill. The size of wire lines which may be used to retract core drills is limited and it would be advantageous to be able to exert a greater retracting force on core drills of this type than is presently possible with wire lines.

This invention provides a hydraulic retractor for drills and is particularly adapted for use with drills of the type shown in the Yancy patent. The retracting force possible with this invention greatly exceeds the force which may be applied by wire line. One factor directly controlling the retracting force is the pressure of mud delivered to the tool through the drill string. As this pressure may be greatly increased by compounding pumps, the retracting force may be increased to any needed value to retract the drill. The retractor does not interfere with continued rotation of the drill, and if necessary, the drill may ream its way back out of the hole in the well wall.

This invention also provides a hydraulic retractor for drills of the type using hydraulic pressure to drive the drill out into a well wall in which the drill is automatically retracted by raising mud pressure above normal drilling pressure to a predetermined higher pressure.

An object of this invention is to provide a hydraulic retractor for the drill of a side wall coring apparatus.

Another object is to provide a hydraulic retractor for the drill of a side wall coring apparatus of the type using hydraulic pressure to drive the drill out into a well wall.

Another object is to provide a hydraulic retractor for the drill of a side wall coring apparatus of the type using hydraulic pressure to drive the drill out into the well and which signals the full extension of the drill either by an increase or decrease in resistance to flow of mud.

Another object is to provide a hydraulic retractor for a core drill which utilizes substantially the full differential between pressure in the open hole and within the drill string.

Another object is to provide a retracting means for a rotary type core drill which may be used while rotation of the drill continues to permit the drill to ream its way back out of the hole in the well wall if necessary.

Another object is to provide a hydraulic retracting means for a core drill which will deliver a hammer blow and then exert a tremendous retracting force on the drill.

Other objects, features and advantages of this invention

will appear from the drawings, the specification, and the claims.

In the drawings wherein there are shown illustrative embodiments of this invention and wherein like reference numerals indicate like parts:

Fig. 1 is a sectional view through a well bore showing a side wall coring apparatus constructed in accordance with this invention taking a core from a side wall of the hole with the tool shown partly in elevation and partly in longitudinal cross section;

Figs. 2A and 2B are views of a fragment of the tool shown in Fig. 1 with the core drill in position to begin taking a core. The views are on an enlarged scale with the tool shown partly in elevation and partly in longitudinal cross section and with Fig. 2B being a continuation of Fig. 2A;

Fig. 3 is a view similar to Figs. 2A and 2B with the core drill in its fully extended position and at the moment of shifting of the valve controlling the retractor means but before the retractor begins to retract the core drill;

Fig. 4 is a view similar to Fig. 3 showing the core drill being retracted from the side wall of the hole; and

Fig. 5 is a fragmentary sectional view of the apparatus shown in Fig. 1 on an enlarged scale using a modified form of core drill in which the operator is signaled that the core drill is fully extended by a drop in pressure instead of an increase in pressure as is the case with the core drill shown in Figs. 1 through 4.

Referring first to Fig. 1, the core taking apparatus illustrated is suspended from the drill string 10. The apparatus includes an upper section 11 which is non-rotatably secured to the drill string and a lower section 12 which is rotatably depended from section 11 through a swivel connection shown in dashed outline at 13. The core drill 14 is rotated by the upper section 11 of the apparatus and is directed by a whipstock 15 in the lower section 12 into the side wall of a well. The lower section 12 is provided with radially extending ribs 16 which engage the wall of the well and hold the section 12 against rotation while the core drill is taking a sample core. For a more detailed explanation of driving and operation of the type of core taking apparatus illustrated, reference is made to the above-identified Yancy patent.

The core drill is shown in its fully extended position with stop 17 on the drill engaging the retractor means indicated generally at 18. At this time the operator will know that the core drill is fully extended by a pressure signal at the slush pump and will raise the pressure in the drill string to operate the retractor mechanism. When the pressure within the drill string reaches a predetermined value, the valve indicated generally at 19 will be shifted to vent the upper side of the retractor mechanism to the open hole. When this occurs, the differential in pressure between the open hole and the pressure within the drill string will be exerted across the retractor mechanism in a direction to drive the core barrel upwardly and retract the core barrel from the side wall of the well.

Reference is now made to Figs. 2A and 2B wherein the details of the mechanism for retracting the core drill are shown. The body of the tool includes a splined driving head 21 at the upper end of the tool. A sleeve valve housing 22 is depended from the head 21 and an outer casing 23 is in turn depended from the housing 22. A mud seal housing 24 interconnects the outer casing with the upper end 25 of the swivel 13. All of these elements of the housing are annular members providing a bore 26 through the housing to accommodate the various elements of the retracting mechanism. These elements are in turn preferably annular in configuration to provide a

bore through the retracting mechanism and the housing through which the core drill 14 is extended.

The core drill 14 is provided at its upper end with a key 26 which is urged by springs 27 radially outward so as to engage the splines 21a of the spline driving head 21. Thus, by rotation of the drill string, rotary movement will be imparted to the core drill.

To provide a hydraulic drive for the core drill, there is provided a core barrel seal 28 in the mud seal housing 24 (Fig. 2B) which seals between the mud seal housing and the core drill. Thus, fluid pressure within the drill string is exerted on the core drill over an area defined by the seal 28 to provide a force urging the core drill out into the formation while the drill is rotated by driving head 21.

Mud circulation during the coring operation is provided by mud passing down the bore through the body of the tool and about the outside of the core drill 14 to the inlets 29 in the core drill. The core drill is hollow below the spline engaging section of the tool and mud passes through the inlets 29 into the hollow interior of the core drill 14 and thence down to the cutting tool 31 (see Fig. 1) to lubricate the cutting tool and remove cuttings from the hole. The holes 29 are adequate to provide for circulation but are sized to permit the operator to maintain the desired pressure drop across the core drill to urge the core drill into the formation.

When the core drill is fully extended the holes 29 will be within the core barrel seal 28 as shown in Fig. 3. When this occurs, the resistance to flow of mud pressure will increase and signal the operator that the core drill has been fully extended. To avoid damage to the mud pump or popping of relief valves, a small diameter inlet 32 is provided in the upper end of the core drill so that some circulation will continue through the tool at all times. This small amount of circulation will prevent a rapid excessive buildup of pressure on the pumps and also will continue mud circulation in the well which is highly desirable.

When the core drill is fully extended a stop provided by sub 17 in the core drill is engaged by the retractor means 18.

The retractor means 18 provides a fluid responsive means for driving the sub 17 and hence the entire core drill upwardly to withdraw it from the side wall of the hole. The retractor means illustrated includes a retractor piston 33 which has a plurality of radially inwardly projecting ribs 34 which engage the stop provided by the sub 17. These ribs provide space through the retractor piston for fluid to flow and reach holes 29 after the holes 29 are below the piston 33 and before they reach the core barrel seal 28.

A sliding seal is provided between the retractor piston and a cylinder liner 35 by suitable packing 36 held on the piston by a piston packing end ring 37 and a snap ring 38. Upwardly extending from the piston 33 there is a retractor piston tube 39 which moves with the piston 33. A sliding seal is provided between the tube 39 and a cylinder head 41 by suitable packing 42. The packing 42 is held in place on the cylinder head by a suitable packing ring 43 and snap ring 44.

The retractor piston 33, retractor tube 39, cylinder liner 35 and cylinder head 41 provide a variable volume chamber 45. If this chamber be subjected to drill string pressure, which will also be present on the underside of piston 33, the piston 33 will merely float in the cylinder liner 35 during normal coring operations. Then if the variable volume chamber 45 be vented to the open hole, a differential will be provided across retractor piston 33 which will drive the piston upwardly and retract the coring drill from the side wall of the hole.

Fluid pressure from the drill string is conducted to the chamber 45 through a ring of ports 46 receiving fluid from an annular gathering ring 47 in the inner wall of the sleeve valve housing 22 (Fig. 2A). Gathering ring

47 receives fluid via annuli 47a and 52a. Fluid is conducted from the ports 46 through the annulus between the inner tube 48 and the outer casing 23 to the annulus between the cylinder liner 35 and the outer casing 23. 5 Grooves 49 in the cylinder head 41 permit fluid to freely pass the cylinder head. Fluid communication is provided between the variable volume chamber 45 and the annulus between the cylinder liner 35 and outer casing 23 by a plurality of holes 51 in the cylinder liner.

10 Through the passageway traced in the last paragraph fluid pressure within the drill string is maintained on the top of the retractor piston 33 and opposes pressure on the bottom of the retractor piston 33. If means be provided for closing off fluid communication between the ports 46 and the bore through the housing and establishing communication between the ports 46 and the exterior of the housing, that is, the open hole, then drill string pressure can be removed from the chamber 45 and a differential equal to the drill string pressure at the retractor piston will be exerted across the piston in a direction to raise the retractor piston.

15 In the illustrated embodiment, the piston-valve 19 (Fig. 2A) provides a means for alternately connecting the ports 46 with the interior of the housing and with the open hole. The piston-valve includes a sleeve valve piston 52 having mounted thereon spaced packing elements 53 and 54. These packing elements provide a sliding seal between the piston-valve 19 and the inner wall of sleeve valve housing 22. It will be noted that the cylinder wall sections provided within the sleeve valve housing 22 for engaging the sliding seals 53 and 54 are of slightly different diameter. The space 55 defined by these sliding seals is connected with the exterior of the housing through a plurality of ports, one of which is shown at 56. The space between the two sliding seals 53 and 54 is always in communication with the open hole. As the opposite ends of the two sliding seals 53 and 54 are exposed to drill string pressure and the end of the piston-valve carrying sliding seal 54 has a pressure responsive surface of slightly larger area than the end of the piston-valve carrying sliding seal 53, there will be provided a pressure responsive area on the piston-valve which tends to urge the valve longitudinally of the tool with a force determined by the pressure within the drill string.

20 During core taking operations, seal 53 connects the ports 46 with the interior of inner tube 48 to pressurize the top of retractor 18. When the piston-valve is shifted by an increase in pressure, seal 53 passes over ports 46 and connects these ports with ports 56 leading to the exterior of the mill to vent the pressure on the top of retractor 18 to the open hole.

25 To prevent shifting of the valve by the action of pressure within the drill string on the piston-valve, there is provided detent means which retains the piston-valve until a predetermined drill string pressure is exerted on piston-valve 19. The detent means illustrated includes a spring 57 and a detent ring 58. The spring 57 is compressed between a lower spring seat 59 welded or otherwise suitably secured within the inner tube 48 and a spring seat ring 61 on the adjacent end of valve 19. The spring 57 also functions to return the valve to the position shown in Fig. 2A after it has been shifted and drill string pressure reduced. The detent ring 58 is held between a detent backup ring 62 and a detent retaining nut 63. The detent backup ring 62 is held in place by a snap ring 64. The nut 63 is threadedly received on the sleeve valve piston 52. A locking pin 65 locks the nut in non-rotative position relative to detent ring 58. A snap ring 66 retains the locking pin in place.

30 The abutting surfaces 63a and 58a of the detent retaining nut 63 and the detent ring 58, respectively, are inclined at acute angles to the longitudinal axis of the tool to provide wedge surfaces which tend to contract the detent ring as the piston-valve moves against spring 57. Surface 58b of the detent ring rests on a surface 67 pro-

vided by an internal annular shoulder within the sleeve valve housing 22 when the piston-valve is in the Fig. 2A position. These surfaces are also inclined to provide wedge surfaces which assist in contracting the wedge ring.

The detent ring 58 is a split ring which, when sufficient force is exerted on the sleeve valve 19, will be forced off of shoulder 67 to permit pressure shifting of the sleeve valve. The force necessary to contract the detent ring and to overcome the resistance to downward movement of the piston-valve offered by spring 57 will be the predetermined force necessary to pressure shift the piston-valve and establish communication between the ports 46 and the ports 56 which lead to the open hole.

In the absence of the detent ring, pressure building up within the drill string would force the piston-valve 19 to slowly move downward to a position at which it would cover the ports 46 while not uncovering the ports 56. This condition would occur before the predetermined pressure for operating the piston-valve when the detent ring 58 is employed. Thus, the maximum working pressure available for normal drilling would have to be reduced or the predetermined pressure at which the valve would open would have to be increased to avoid the occurrence of a differential across the retracting piston 33 during normal drilling operations which would oppose the force of fluid pressure urging the core drill out into the well. As the effective area of the retracting piston is much larger than the effective pressure responsive area of the core drill, a relatively small differential across the retracting piston would be objectionable because it would tend to reduce the force with which the core bit is urged into the formation.

The detent ring provides a snap action for the piston-valve 19 which will drive the piston-valve down to a position at which the ports 46 will be completely uncovered and their full area will be available for effective bleeding of pressure from the variable volume chamber 45. As the fluid within the variable volume chamber 45 will be a liquid, only a small amount need be exhausted from the chamber to equalize pressure within the chamber 45 with the open hole and, therefore, a very rapid build-up in differential across the retracting piston 33 will occur. This will provide a hammer action which, even with the coring tool in fully extended position, will be effective on the cutting end of the coring tool. The hammer blow is permitted by the slight play in the swivel joints 68 and 69 in the coring drill and by straightening out of the angles provided by the swivel joints when the core bit begins its upward movement. Also, the entire lower portion 12 of the assembly will tend to move over toward the portion of the side wall of the well in which a hole has been cut by the coring tool to provide additional lost motion. While this lost motion will be small, it will provide a hammer blow.

It is believed that operation of the tool is apparent from the above detailed explanation but it will be summarized here for convenience. The core taking assembly illustrated minus the core drill is made up on the lower end of a drill string and run into the hole to the desired depth. The core drill 14 is then run in the hole on a wire line until the driving key 26 engages the spline section 21. The string is then suspended from the kelly in the rotary table for rotation in the usual manner. At this time the apparatus will be as illustrated in Figs. 2A and 2B.

Fluid pressure from the slush pumps is applied in the usual manner within the drill string to urge the coring bit out into the formation while at the same time the string is rotated by the rotary table. Pressure on the coring bit forces it against the side wall and the blades 16 engage the side wall of the hole on the opposite side from the whipstock 15 to prevent rotation of the lower section of the tool. Primary mud circulation is provided

through the inlets 29 into the hollow core drill and passes through the drill to the cutting end 31 of the tool where it washes cuttings from the hole and lubricates the tool.

When the core drill has been moved down in the assembly a predetermined length, the holes 29 pass into the core barrel seal 28 and prevent flow of mud into the core barrel through these ports. While some flow still continues through the bleed inlet 32, the resistance to flow of mud is raised a considerable amount to signal the operator that the core bit has been fully extended. This condition is illustrated in Fig. 1. At this time mud pressure is increased to a value greater than the predetermined pressure at which the piston-valve 19 will shift and this pressure will cause the detent ring 58 to be contracted and the piston valve to shift to its down position. This will place the ports 46 and 56 in communication with each other and drill string pressure which has been conducted to the variable volume chamber 45 through the entryway provided by ports 46 during drilling operations will now be vented to the open hole through ports 56. This condition is shown in Fig. 3. When this occurs the drill string pressure will be exerted across the retracting piston 33 in an upward direction and the piston will move upwardly engaging the stop 17 on the core drill to raise the core drill to its retracted position. The retracting piston will, of course, move upwardly until it engages the cylinder head 41. Fig. 4 illustrates the core drill being raised.

In the event the core barrel sticks in the formation and does not come free, then the rotary table may be started up again, if it has been stopped, and the combined upward force and rotary force on the core barrel will permit the core barrel to ream its way back out of the hole in the side wall of the formation.

As an alternative, the pressure within the drill string may be increased and decreased across the predetermined pressure at which the piston-valve 19 is operated to alternately connect the variable volume chamber 45 with the high pressure within the drill string and with the open hole pressure to apply successive hammer blows and pulls on the coring tool.

It is noted that when the core barrel reaches a partly retracted position the ports 29 will be retracted from the core barrel seal 28 and there will be a drop in resistance to flow of drilling mud. This will indicate to the operator that he has broken the core loose and has obtained at least initial movement of the core bit toward retracted position.

After the core bit has been retracted, the string is lifted to place slips in the rotary table about the top section of the drill string and the kelly may then be removed. A wire line is run in the hole to engage the core barrel and bring it to the surface. At this time the entire assembly may be removed from the hole or additional core bits may be run and the operation repeated successively as many times as is desired to obtain the desired cores from the well.

Fig. 5 illustrates a modified form of core drill in which mud circulation is provided by introducing mud into the upper end of the core drill through inlets 71. A plurality of ports 72 are provided in the core bit at a point below the stop sub 17 and during normal coring some fluid will also enter the core barrel through these holes. As these holes pass through the core barrel seal 28, they permit fluid entering through the primary inlet 71 into the core barrel to exhaust through the holes 72 into the swivel joint and thence into the open hole. In this manner resistance to flow of mud is reduced and this reduction in pressure signals the operator at the surface that the core bit is fully extended.

In this form of tool pressure drop across the core drill is provided for downstream of the holes 72. See the Yancy patent. Thereafter, the operator increases pressure within the drill string in the same manner as heretofore explained to operate the sleeve valve 19 and raise the retracting piston

33 to retract the core bit from the wall of the well. Inasmuch as mud is flowing into the open hole through the ports 72, it will be appreciated that a greater pump capacity will be required to obtain the same pressure conditions as are possible in the Figs. 1 through 4 illustrated embodiment and, therefore, it is preferred to use the form of core bit which signals full extension of the core bit by an increase in pressure rather than a decrease in pressure.

From the foregoing it will be seen that this invention is one well adapted to attain all of the ends and objects hereinabove set forth, together with other advantages which are obvious and which are inherent to the apparatus.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, port means for fluidly connecting the chamber with the passageway and with the exterior of the body, valve means operable to control flow through the port means so that said chamber is alternately connected with the passageway and the exterior of the body, and means for operating the valve means in response to predetermined pressure conditions in the passageway.

2. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, port means for fluidly connecting the chamber with the passageway and with the exterior of the body, valve means operable to control flow through the port means so that said chamber is alternately connected with the passageway and the exterior of the body, and piston means for shifting the valve means from a position connecting the chamber with the passageway to a position connecting the chamber with the exterior of the body in response to a predetermined high pressure in the fluid passageway.

3. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, port means for fluidly connecting the chamber with the passageway and with the exterior of the body, valve means operable to control flow through the port means so that said chamber is alternately connected with the passageway and the exterior of the body, piston means connected to the valve means to shift the same from a position connecting the chamber with the passageway to a position connecting the chamber with the exterior of the body in response to a predetermined high pressure in the passageway, and detent means holding the piston means in unshifted position until said predetermined pressure conditions exist in the passageway.

4. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, a combination piston-slide valve having spaced seals engaging spaced cylinder wall sections of the body, said piston-slide valve having opposed pressure responsive surfaces of different area exposed to pressure in the passageway, port means interconnecting the space defined by said seals with the exterior of the body, resilient means urging the piston-valve in a direction from the smaller pressure responsive surface toward the larger pressure responsive surface, and port means interconnecting the chamber with one of the cylinder wall sections at a point outside of said spaced seals when the piston-valve is in its resilient means urged position and between said seals when the piston-valve is shifted by pressure in the passageway against the resilient means.

5. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, a combination piston-slide valve having spaced seals engaging spaced cylinder wall sections of the body, said piston-slide valve having opposed pressure responsive surfaces of different area exposed to pressure in the passageway, port means interconnecting the space defined by said seals with the exterior of the body, detent means including resilient means urging the piston-valve in a direction from the smaller pressure responsive surface toward the larger pressure responsive surface preventing pressure shifting of the piston-valve until pressure in the passageway reaches a predetermined high pressure, and port means interconnecting the chamber with one of the cylinder wall sections at a point outside of said spaced seals when the piston-valve is in its resilient means urged position and between said seals when the piston-valve is shifted by pressure in the passageway against the resilient means.

6. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, a combination sleeve-piston-slide valve having spaced annular seals engaging longitudinally spaced cylinder wall body sections of different diameter and providing opposed pressure responsive surfaces on the piston-valve of different area exposed to pressure in the passageway, port means interconnecting the space defined by said seals with the exterior of the body, resilient means urging the piston-valve in a direction from the smaller pressure responsive surface toward the larger pressure responsive surface, and port means interconnecting the chamber with the smaller diameter cylinder wall section at a point outside of the spaced seals when the piston-valve is in its resilient means urged position and between said seals when the piston-valve is shifted by pressure in the passageway against the resilient means.

7. A side wall coring tool comprising, a body having a passageway therein adapted to be run on a drill string, a piston in said body, retractor means carried by the piston for retracting a side wall core drill from the wall of a well into the passageway, a chamber in said body, said piston exposed on one side to the passageway and on the other side to the chamber, a combination sleeve-piston-slide valve having spaced annular seals engaging

longitudinally spaced cylinder wall body sections of different diameter and providing opposed pressure responsive surfaces on the piston-valve of different area exposed to pressure in the passageway, port means interconnecting the space defined by said seals with the exterior of the body, detent means including resilient means urging the piston-valve in a direction from the smaller pressure responsive surface toward the larger pressure responsive surface and preventing pressure shifting of the piston-valve until pressure in the passageway reaches a predetermined high pressure, and port means interconnecting the chamber with the smaller diameter cylinder wall section at a point outside of the spaced seals when the piston-valve is in its resilient means urged position and between said seals when the piston-valve is shifted by pressure in the passageway against the resilient means.

8. A side wall coring tool comprising, an elongate body having a longitudinal bore therein adapted to be run on a drill string, a side wall core drill adapted to be received in the bore of said body and to be directed into the side wall of a well to take a core, a stop on the core drill, retractor means in the body and engageable with the stop on the core drill to retract the core drill from the wall of a well into the bore of the body, said retractor means including a piston mounted in said body, a chamber in said body, said piston exposed on one side to the bore through the body and on the other side to the chamber, port means for fluidly connecting the chamber with the bore and with the exterior of the body, valve means operable to control flow through the port means so that said chamber is alternately connected with the bore through the body and the exterior of the body, and means for operating the valve means in response to predetermined pressure conditions in the bore.

9. A side wall coring tool comprising, an elongate body having a longitudinal bore therein adapted to be run on a drill string, a side wall core drill adapted to be received in the bore of said body and to be directed into the side wall of a well to take a core, a stop on the core drill, retractor means in the body and engageable with the stop on the core drill to retract the core drill from the wall of a well into the bore of the body, said retractor means including a piston mounted in said body, a chamber in said body, said piston exposed on one side to the bore through the body and on the other side to the chamber, port means for fluidly connecting the chamber with the bore and with the exterior of the body, valve means operable to control flow through the port means so that said chamber is alternately connected with the bore through the body and the exterior of the body, and piston means for shifting the valve means from a position connecting the chamber with the bore of the body to a position connecting the chamber with the exterior of the body in response to a predetermined high pressure in the bore of the body.

10. A side wall coring tool comprising, an elongate body having a longitudinal bore therein adapted to be run on a drill string, a side wall core drill adapted to be received in the bore of said body and to be directed into the side wall of a well to take a core, a stop on the core drill, retractor means in the body and engageable with the stop on the core drill to retract the core drill from the wall of a well into bore of the body, said retractor means including a piston mounted in said body, a chamber in said body, said piston exposed on one side to the bore through the body and on the other side to the chamber, port means for fluidly connecting the chamber with the bore and with the exterior of the body, valve means operable to control flow through the port

means so that said chamber is alternately connected with the bore through the body and the exterior of the body, piston means for shifting the valve means from a position connecting the chamber with the bore of the body to a position connecting the chamber with the exterior of the body in response to a predetermined high pressure in the bore of the body, and detent means holding the piston means in unshifted position until said predetermined pressure condition exists in the bore.

- 10 11. A side wall coring tool comprising, an elongate body having a longitudinal bore therein adapted to be run on a drill string, a side wall core drill adapted to be received in the bore of said body and to be directed into the side wall of a well to take a core, a stop on the core drill, retractor means in the body and engageable with the stop on the core drill to retract the core drill from the wall of a well into the bore of the body, said retractor means including a piston mounted in said body, a chamber in said body, said piston exposed on one side to the bore through the body and on the other side to the chamber, a combination piston-slide valve having spaced seals engaging spaced cylinder wall sections of the body, said piston-valve having opposed pressure responsive surfaces of different area exposed to pressure in the bore, port means interconnecting the space defined by said seals with the exterior of the body, resilient means urging the piston-valve in a direction from the smaller pressure responsive surface toward the larger pressure responsive surface, and port means interconnecting the chamber with one of the cylinder walls at a point outside of said spaced seals when the piston-valve is in its resilient means urged position and between said seals when the piston-valve is shifted by pressure in the bore of the body against the resilient means.
- 15 12. A side wall coring tool comprising, an elongate body having a longitudinal bore therein adapted to be run on a drill string, a side wall core drill adapted to be received in the bore of said body and to be directed into the side wall of a well to take a core, a stop on the core drill, retractor means in the body and engageable with the stop on the core drill to retract the core drill from the wall of a well into the bore of the body, said retractor means including a piston mounted in said body, a chamber in said body, said piston exposed on one side to the bore through the body and on the other side to the chamber, a combination piston-slide valve having spaced seals engaging spaced cylinder wall sections of the body, said piston-valve having opposed pressure responsive surfaces of different area exposed to pressure in the bore, port means interconnecting the space defined by said seals with the exterior of the body, detent means including resilient means urging the piston-valve in a direction from the smaller pressure responsive surface toward the larger pressure responsive surface and preventing pressure shifting of the piston-valve until the pressure in the bore of the body reaches a predetermined high pressure, and port means interconnecting the chamber with one of the cylinder walls at a point outside of said spaced seals when the piston-valve is in its resilient means urged position and between said seals when the piston-valve is shifted by pressure in the bore of the body against the resilient means.
